US00D646156S

(12) **United States Design Patent**
Maxwell-Wood

(10) **Patent No.:** US D646,156 S
(45) **Date of Patent:** ** Oct. 4, 2011

(54) **BISCUIT BOX**

- (75) Inventor: **Thomas Hedley Maxwell-Wood**, Wantage (GB)
- (73) Assignee: **Crown Packaging Technology, Inc.**, Alsip, IL (US)
- (**) Term: **14 Years**

(21) Appl. No.: **29/343,691**

(22) Filed: **Sep. 17, 2009**

(51) LOC (9) Cl. **09-03**

(52) U.S. Cl. **D9/414; D9/432**
